LOUI F. HECK, OF LITTLE ROCK, ARKANSAS, ASSIGNOR OF ONE-HALF TO
DANIEL G. FONES, JAMES A. FONES, THOMAS T. JOHNSON, AND LOUIS K.
MANDLEBAUM, ALL OF SAME PLACE.

SAFETY ATTACHMENT FOR FARE-BOXES.

SPECIFICATION forming part of Letters Patent No. 416,915, dated December 10, 1889.

Application filed February 5, 1887. Serial No. 226,626. (Model.)

To all whom it may concern:

Be it known that I, LOUI F. HECK, of Little Rock, in the county of Pulaski and State of Arkansas, have invented certain new and useful Improvements in Safety Attachments for Fare-Boxes; and I do hereby declare the following to be a full, clear, and exact description of the invention, such as will enable others skilled in the art to which it appertains

1c to make and use the same.

My invention relates to an improvement in safety attachments for fare-boxes.

The nature and object of my present invention are to provide a secure and convenient device whereby the deposited fares may be removed from the fare-receptacle of an ordinary fare-receiver, and that is adapted to automatically open a passage from the fare-deposit chamber into a receiving-bag or portable fare-container and close and lock both the passage from the fixed fare-deposit chamber and the passage into the portable fare-receiver when this latter-mentioned receptacle is removed from its temporary attachment on the base of a fixed fare-box.

25 With this object in view my invention consists in certain features of construction and combinations of parts that will be hereinafter described, and pointed out in the claims.

30 In the accompanying drawings, Figure 1 is a side and top view of the attachment with the lock and ferrule of the portable receiver in position to enter the slideway in the stationary frame of the device. Fig. 2 is a 35 plan view of the receiver-lock with top removed to show its interior, the receiver being in connection with the frame that is secured to a fare-box and adjusted to open a clear passage from the deposit-chamber of the

40 fare-box to the interior of the receiver. Fig. 3 is a view of the lower side of the frame of the safety attachment with a portion of the enveloping shell removed to expose working parts. Fig. 4 represents a bottom and side view of the locking attachment that is fixed to the lower end of the fare-box, a portion of the shell on the side being broken away to expose details. Fig. 5 shows a longitudinal section of connected parts of the device, the

lock of the receiver being in detached adjustment and held to re-engage the neck-flange of the fare-receiver when this is removed from the position given it when cash is transferred from the fare-box to the portable receiver. Fig. 6 is a view of the vibrating guard-lock 55 removed from its supporting frame. Fig. 7 exhibits an end elevation of the fare-receiver and its attached lock.

To carry into effect the purposes of this invention a fixed mechanical device is combined with the fare-deposit box of an ordinary fare-box. This mechanism embodies a guard-lock that acts in conjunction with a lock that is removably connected to the upper end or neck of a flexible portable fare-receiver. The receiver automatically coacts with the guard-lock, that is secured to the lower end of the fare-box proper to open a continuous way or passage from the fixed fare-box to the temporarily-attached portable fare-receiver, which 70 can be removed, locking the guard-lock on the bottom of the fixed fare-box, and also connecting a lock-case and its contained lock that is locked in place upon the discharge-orifice of the portable receiver to prevent access thereto until a proper key is used to give authorized access to the fares deposited within such a receptacle.

75 I will proceed to describe the fixed mechanism attached to the base of a fare-box. 80

A is a containing-case, by which the device is secured in place to the lower end of an ordinary fare-box fixed in a horse or steam car used for passenger purposes. The metallic frame B is made to fit the case A, this frame 85 being provided to sustain the contained mechanism in operative position.

The lower face of the case A is provided with parallel guide-ledges J J. (Shown in dotted lines in Fig. 2.) These guides support 90 in sliding position the gate C, and this gate is made with two horizontal walls that are parallel to each other, the lower wall conforming to the inner surface of the bottom plate A³ of the case A. Reference to Fig. 4 95 will show a portion of the plate A³ removed from A³ to A⁴, producing a semicircular edge at A³, the parallel portions of the said plate

extending from A⁴ to A⁵, (see Fig. 4,) the guide-ledges J J being secured to the inner edges of these parallel portions of plate A², rendering these parts stable, the guide-ledges 5 J J being cut away at their front ends to form inclines, for a purpose that will be hereinafter shown.

The front end of the sliding gate C (see Fig. 5) is closed to connect the top and bottom sides of the same, the vertical wall thus produced at G³ being grooved to form a hook that extends across the front end of the gate, as shown at G² in Fig. 5.

The frame B is cut away at s, Figs. 3 and 4, 15 to afford space for the bodies of the hooks F, which are rigidly fastened by their rear ends to the side walls of the gate C. The frame B has an integral cover D², made to extend across from its side walls, the lower surface 20 of this cover having sufficient clearance space between it and the bottom plate A² of the case A to allow the sliding gate C to reciprocate between these parallel surfaces, neatly fitting the space allowed for its travel. 25 The cylindrical tube D' is made to project vertically from the cover D², this tube being intended to form a communicating passage with the cash-chamber of the fare-box upon which the device is secured, and it will be 30 noticed in Fig. 5 that a funnel or hopper shaped bottom is formed on the cash-chamber to lead its contents to the tube D', from which it may be made to escape downwardly when the mechanism is properly adjusted to 35 permit it. The horizontal wall or cover D² terminates at a point D³, (see Fig. 5,) and a vertical wall D⁴ is formed integral with the front side wall of the tube D'. Between this vertical wall D⁴ and the end of the frame B 40 a guard-lock E is pivoted upon the trunnions 55 to permit it to have a slight vibratory movement upon these pivotal points as a center. (See Figs. 2 and 6.) The sides of the guard-lock are constructed each having 45 three parallel walls 1 3 4, that leave intersecting spaces of a proper width. Between the walls 3 4 the locking-bars f g are located. These are provided with toes f² g³, that are intended to engage the notches 50 e e', formed in the side wall of the frame B, near the corners of the same. (See Fig. 2.) The location of these notches e e' is such that the locking-bars f g will enter them when the frame E of the guard-lock is in an inclined 55 position, as seen in Fig. 1, the withdrawn bolts and the receiving-notches being shown in Figs. 2 and 3. Two wire springs f³ g⁴ are secured to the inner edge of the guard-lock frame E, their free ends bearing upon the opposed ends of the locking-bars f g to cause 60 them to engage their notches when this lock-frame E is tipped or inclined to cause the notches and ends of the bars to line with each other. A projecting ear g² is formed on the 65 side of the bar g to enter the slot g⁴ in the frame B, this slot having a branch slot g⁵, made to communicate with it to permit the

ear g² to enter it when the frame E of the guard-lock is made to lie in a horizontal position.

A short locking-bolt m is held in place to slide against the wall 1 of the guard-lock E, and it is actuated by the finger-spring m', which bears upon its bent forward end. The wall 1 is thickened or made to extend into the space occupied by the bolt m to act as a guard in advance of this locking-bolt, and thus prevent the use of a picking-tool from the outer end of the slot to disengage the bolt. The free end of the bolt m is made to extend 80 into the slot 13 in the side of the frame B, (see Fig. 4,) and a branch slot 12 is downwardly extended from slot 13 to allow the end of the bolt m to enter it when the bolt is shoved to cause its end to line with the slot, 85 and the lock-frame E is rocked on its trunnions to cause the frame to lie parallel with the gate C. The outer walls 3 of the frame E (see Fig. 6) are inwardly extended at a right angle to produce horizontal flanges 14 90 on each side of the frame, these being designed to form a slideway for the connected lock G and ferrule D of the portable fare-receiver D⁵, a sufficient space being allowed to permit the horizontal integral flange G⁴ of the 95 ferrule D to be inserted between the flanges 14 and horizontal portions u of the frame E, and it will be noticed that the vertical walls 2 2 of this frame are free from connection with the cap-plate of the lock-frame to provide open slots for the reception of the case 100 of the lock G. The flanges 14 are made to fit into notches a² in the guide-ledges J J when the lock-frame E is in an inclined position, the notches a² being shown in Fig. 5, 105 and the engagement of parts just described is exhibited in Fig. 4, and it is apparent that the sloping edges of the guide-ledges J J, together with the flanges 14, will form a continuous slideway for the easy introduction of 110 the flange G' of the ferrule D, to which the portable fare-receiver D⁵ is secured by wire wrapping W or other suitable means.

The fare-receiver consists of a cylindrical ferrule D, to which the portable fare-receiver 115 D⁵ is secured, as just stated, a novel lock, with its frame, being made to have sliding and locked engagement with the flange G', integrally formed upon the upper part of the ferrule. (See Fig. 7.)

The lock-case G is made of plate metal and has depending flanges b b, formed integral with the top plate. These are made to extend downwardly and leave a narrow slit between their free ends and the upper surface of the laterally-extended flanges G⁴ of the base-plate of the lock. Openings v v' are provided at each end of the vertical front plate G⁶ of the lock-case G. (See Fig. 7.)

The mechanism of the lock of the portable 130 fare-receiver D⁵ is a modified form of a tumbler-lock of approved construction, which is adapted to suit the service to which it is applied. It consists, essentially, of a flat slide-

bolt O. (See Fig. 2.) This bolt O is cut away to receive the cylindrical key-post V, supported in vertical position by the insertion of a short journal end u^4 into a perforation 5 made to receive it in the base-plate G⁸ of the lock-case G. (See Fig. 5.) The upper end of the key-post V is retained in place by a short collet u' , (see Fig. 2,) made integral with the top plate of the lock, the key-post being thus 10 held to be rotated by the key, which is inserted in the lock to remove it from the flange G' when access is desired to the interior of the receptacle D⁵, a key-slot u^2 being cut in the body of the post V to allow the key to 15 enter the lock.

A lateral projection x is made on the key-post V and adapted to slide beneath the spring-actuated tumblers h h' and permit the key to operate the tumblers and bring their 20 slots p in line, so that the projecting guard-stud p', which is fixed upon the slide-bolt O, will enter these tumbler-slots and allow the slide-bolt O to slide under the action of the projection x, which, with the turn of the key, 25 impinges the edge of a slot x', formed in the bolt. Now, in order to render the operation of this lock automatic, the tumblers h h' are furnished with extended limbs h² h³, which 30 project to cross the opening or space v', formed in the lock-case G. The tumblers thus constructed will be operated to bring their slots in alignment by the combined spring action 35 of the limbs h² h³ and the abutment of the wards of the key to permit the bolt O to slide laterally, this abutment taking place when 40 the locked portable receptacle D⁵ is made to have connection with the fixed fare-box attachment, of which B is the frame, and which has been previously described. The bolt O 45 is made to engage the bell-crank I, which is pivoted at I² and has its free end I' made to project into the open space v of the lock-case G. A jointed bar F² is pivoted at 10, (see Fig. 5,) and is made to extend lengthwise of 50 the frame B, (see Fig. 2,) its forward end F³ being opposite the projecting end I' of the bell-crank I. The normal position of the jointed bar F² is shown in Fig. 1, and it will be noticed that the bar is bent at its joint l, 55 which has the effect of slightly shortening it. This position of the bar is assumed when the portable fare-receiver is disengaged, as shown in this figure.

When the lock-case and its attached fare-receptacle is inserted and made to slide into the open end E' of the frame B and up the inclines a a, the toe I' of the bell-crank I in the lock G will come opposite the end F³ of the bar F², and when the guard-lock is vibrated 60 on its trunnions 5 to bring its frame parallel with the sliding gate C the portion of the jointed bar F² that enters the lock-case G will afford a purchase upon the bar to straighten and thus lengthen it, causing its end F³ to abut upon the free end or toe I' of the bell-crank I, as shown in Fig. 2, which represents the lock-case G in position in the

guard-lock frame E. With this frame E in a level position the abutment of the bar with the bell-crank just described will have a 70 tendency to slide the projecting lug e³, formed on the slide-bar O, and thus release this catch from locking engagement with the flange G', which flange laterally extends from the ferrule D, being made to slide in the guideways 75 y y, formed in the base-plate G⁴ of lock-case G. (See Fig. 7 and also Fig. 3.) In this plate the open slot i and locking-shoulder i' are shown, as well as the projecting lug e³, in position to enter the slot and be 80 locked to the shoulder i', or upon the inside of the ferrule D, as shown in dotted lines in Fig. 3.

Reference to Fig. 2 will show a hook t secured to the inner surface of the side wall 2 85 of the lock-case G. This hook is of sufficient length to permit its shoulder to engage with the end of the locking-bolt m. Said bolt forms a portion of the securing mechanism 90 of the guard-lock E, the relative proportion and location of the hook t and bolt m being such that the insertion of the lock-case G into proper place in the guard-lock frame E will cause the bolt m to move lengthwise and dislodge it from its locking contact in the 95 slot 13 and bring it opposite the slot 12. The spring g', that has bearing contact with the bent end of the bolt m, will yield when this contact of parts takes place.

Upon the frontedge of the flange G' a hook 100 or depending rib G² is formed on its under side to engage with the groove made on the transverse wall G³ of the sliding gate C to effect a locked connection of the flange and gate when the gate C is closed and the lock 105 G is inserted and depressed to a position in the same horizontal plane with this gate, as shown in Fig. 5.

In operating the portable fare-receiver its attached ferrule D and lock G are inserted in 110 place in connection with the pivoted guard-lock G, the side walls of the lock-case G and hook t in the lock G impinging upon the locking-bars f, g, and m of the guard-lock E, releasing their secured contact with the slots e 115 e' and 13 g' of the frame B, so that the frame may be vibrated sufficiently to bring it level. The toes g² of the bar g and m of that sliding bolt m will enter the branch slots g⁵ and 12 of the frame B and permit such an oscillation 120 of the frame. Simultaneously with the operation just mentioned the depression of the lock-frame to form hooked engagement with the gate C will straighten the jointed bar F², and thus disengage the catch e³ from the ferrule D and its attached plate G⁴ by action of 125 the bell-crank I, which the bar F² abuts upon. The tumblers h h' are brought into proper position to allow the bell-crank I to move the connected bolt O and its attached lug e³ by the 130 abutment of the end of the wall 2 of the guard-lock E. When the lock E is properly engaged with the gate C, the release of the lug e³ will allow the ferrule D, its flange G', and the at-

tached fare-receptacle D⁵ to be slid into line with the tube D', and thus afford a continuous passage from the fare-deposit chamber of a fixed fare-box into the removable fare-receptacle D⁵, the gate C being caused to slide back into the position shown in Fig. 5. The hooks H, that project forward to engage the front edges of the side walls 3 of the frame of the guard-lock E, are released from locking 10 engagement therewith when the guard-lock E is raised to the position shown in Fig. 5, said hooks being shown in dotted lines. When the fares are transferred to the portable fare-receiver D⁵, the simple retractile movement 15 of this detachable portion of the apparatus will cause the flange G' of the ferrule D to enter the guideways y y on the base-plate G⁴ of the lock G. When this movement has caused the hooks H on the sliding gate C to 20 strike upon the front portion of the frame B, the lock G and flange G' will be correctly adjusted in relation to each other, and the guard-lock E may be tipped or inclined, as shown in Fig. 1, which movement, when completed, 25 will secure the lock G and flanged ferrule together, the several bolts of the guard-lock will assume a normal or locked position in their slots, and the portable fare-receiver may be slid out of the frame B with its contents 30 sealed intact, and cannot be removed without a proper key or a mutilation of the receptacle.

The lock that is affixed to the fare-receptacle D⁵ may be altered in regard to its tumblers to permit different-shaped wards cut in each 35 key to prevent a uniformity of the locks and keys.

Other slight changes might be made in the constructive features of this device without a violation of the spirit or exceeding the 40 legitimate scope of my invention. I do not therefore desire to restrict myself to the exact forms herein shown; but,

Having fully described my invention, what I claim as new, and desire to secure by Letters 45 Patent, is—

1. In a safety attachment for fare-boxes, the combination, with a frame and a lock-frame pivoted in said frame, of a removable fare-receiver and a lock adapted to automatically 50 close and open the mouth of the receiver by its passage through the lock-frame, substantially as set forth.

2. The combination, with a frame and a lock-frame pivoted therein, of a removable fare-receiver and a lock for automatically closing and opening the mouth of the receiver by its passage through the lock-frame, substantially as set forth.

3. The combination, with a frame and a lock-frame pivoted therein, of a removable fare-receiver, a lock for automatically closing the mouth of the receiver by its passage through the lock-frame, and a sliding gate adapted to close the inlet of the frame when 65 the receiver is removed, substantially as set forth.

4. The combination, with a frame, secured

to a fare-box and a pivoted lock-frame, of a removable fare-receiver and a guard-lock adapted to close the mouth of the receiver 70 while passing through the lock-frame, substantially as set forth.

5. The combination, with a frame having a fare-inlet, of a removable fare-receiver and a sliding gate adapted to interlock with the 75 latter and close the inlet by the removal of the receiver from the frame, substantially as set forth.

6. In a safety attachment for fare-boxes, the combination, with a frame secured to the 80 fare-box, of a removable fare-receiver, a lock for automatically closing the mouth of the receiver, and a sliding gate adapted to close the outlet of the fare-box when the receiver is removed, substantially as set forth. 85

7. In a safety attachment for fare-boxes, the combination, with a rectangular frame provided with guide-ledges, of a sliding gate provided with hooks and a pivoted guard-lock that holds the gate in closed position 90 when the front end of the guard-lock is depressed to engage the hooks of the gate, substantially as set forth.

8. In a safety attachment for fare-boxes, the combination, with a rectangular frame, a vertical fare-conducting tube, and a sliding gate 95 having hooks extended from its end, of a pivoted guard-lock adapted to lock in an inclined position while in locked adjustment with the extended hooks of the sliding gate, substantially as set forth. 100

9. In a safety attachment for fare-boxes, the combination, with a rectangular frame, a sliding gate, and a guard-lock pivoted to vibrate in the frame and be locked in an inclined position thereto, of a portable fare-receiver and its lock, which is adapted to slide the locking-bolts of the guard-lock to permit it to be vibrated on its trunnions, substantially as set forth. 110

10. In a safety attachment for fare-boxes, the combination, with a rectangular frame, its vertical fare-conducting tube, guideways, and sliding gate, of a pivoted guard-lock that locks itself in an inclined position, and also locks 115 the gate to close the box of the fare-conducting tube when the guard-lock is in a secured inclined adjustment, substantially as set forth. 120

11. In a safety attachment for fare-boxes, 120 the combination, with a rectangular frame and its vibrating guard-lock and a sliding gate provided with a grooved front edge, of a portable fare-receiver and its detachable lock, the fare-receiver being furnished with a 125 hooked flange that is adapted to engage the groove of the sliding gate and move it when the guard-lock is vibrated to throw it in a plane parallel to the face of the sliding gate, substantially as set forth. 130

12. In a safety attachment for fare-boxes, the combination, with a rectangular frame, its sliding gate, a fare-conducting tube that is closed by the gate, and a pivoted guard-lock

that holds the gate in closed adjustment, of a portable fare-receiver provided with a lock that is adapted to be released from the receiver and be held in position in the frame of the guard-lock to re-engage the flange of the ferrule of the receiver and be locked thereto when the receiver is removed from engagement with a fixed fare-box to which the rectangular frame is attached, substantially as set forth.

13. A safety attachment for fare-boxes, consisting, essentially, of a rectangular frame, a fare-conducting tube, a sliding gate to close this tube, a guard-lock that is pivoted to oscillate in the frame and lock thereto in an inclined position, two extended hooks that are

attached to the sliding gate and that engage the inclined end of the guard-lock frame, and a portable fare-receiver, with its detachable lock that coacts with the guard-lock and sliding gate to afford a passage from the fixed fare-box to the portable receiver and close both the fare box and receiver when the receiver is withdrawn from connection with the fare-box, substantially as set forth.

25 In testimony whereof I have signed this specification in the presence of two subscribing witnesses.
